UNITED STATES PATENT OFFICE.

HENRY E. TRUMBLE, OF KALAMAZOO, MICHIGAN.

WATER-MOTOR.

SPECIFICATION forming part of Letters Patent No. 431,156, dated July 1, 1890.

Application filed September 2, 1889. Serial No. 322,670. (No model.)

To all whom it may concern:

Be it known that I, HENRY E. TRUMBLE, a citizen of the United States, residing at Kalamazoo, county of Kalamazoo, State of Michigan, have invented a new and useful Water-Motor, of which the following is a specification.

This invention relates to that class of water-motors in which the piston consists of two plates end to end and jointedly connected together, and in which the end of one of the plates is pivoted at a fixed point and the free end of the other plate acts as a cut-off valve at the induction-port.

15 The object of the invention consists in a construction whereby the end of the piston which serves as the cut-off is controlled and timed in its movement independently of the action of the water at the induction-port.

20 Other objects in relation to the induction-port and exhaust-ports will appear in the following description and claims.

In the drawings forming a part of this specification, Figure 1 is a side elevation with 25 one of the walls of the flume removed and parts broken away; Fig. 2, an end elevation looking from a point at the left in Fig. 1. Fig. 3 is an end elevation looking from a point at the right of Fig. 1. Fig. 4 is a section of 30 the left-hand end of Fig. 1 on line 3 3 in Fig. 2, looking from a point above. Fig. 5 is a sectional view of the right-hand end of Fig. 1 on line 4 4 in Fig. 3, looking from a point above. Fig. 6 shows lettered details from 35 Fig. 1, and Fig. 7 shows enlarged letter details at the left in Fig. 1.

Referring to the lettered and numeral parts of the drawings, A is an elongated rectangular flume, in which the piston is located and 40 through which the water flows. The piston consists of two plates G and B end to end and jointedly connected together, as in Fig. 1, one end of the rear plate B being pivoted in the flume at r, Figs. 1 and 5.

45 At 1 is a piston-rod attached to the piston at one end and by a pitman F to the crank-disk 2 of an ordinary power-shaft, said pitman being pivoted to the piston-rod at O, said piston-rod of course passing through the wall 50 of the flume.

3 is a centrally-pivoted lever, and c is a rod pivotally attached at the upper end to one

end of said lever 3 and at the lower end, at m, to the free end of the plate G of the piston.

55

The object of this construction is explained as follows: When the piston is in the position shown in Fig. 1, the rear end of the lever 3 rests against the projection x on piston-rod 1, and thus the front end of the plate G is 60 raised to the angle shown in Fig. 1. When in this position, the water which flowed through the flume above the piston is shut off by the gate a, with which the end of the plate G comes in contact, and the water then 65 flows through the flume beneath the piston. The gates a are held out to place by springs, as at the lower left-hand corner in Fig. 1.

At i is a bar adapted to yield against the springs t, said springs being between the ends 70 of said bar i and the end standard R of the flume A, as in Figs. 1 and 7. Attached adjustably to bar i are castings e, held by setscrew 4 4. These castings e are provided with spring-plates n, and the end of the plate G of 75 the piston comes in contact with said plates n during the reciprocating movements of the piston. The object of having the bar i yield against a spring-resistance is to accommodate the lengthening and shortening of the jointed 80 piston when it comes in contact with the spring-plates n of the castings e. Said castings are provided with shoulders 5, against which the end of the plate G catches for the purpose of holding said plate G of the piston 85 from tilting too soon.

In Fig. 1 the water flowing through the induction-port beneath the piston will raise the latter upward to a position opposite to that shown in said figure, and when the joint of 90 the piston has reached the upper side of the flume the free end of the plate G will be released from the shoulder 5 of the upper casting e, and said plate G will tilt against the lower gate a and will be held in a position 95 opposite to that in Fig. 1 against the shoulder 5 of the lower casting e through the medium of the lever 3, the rear end of which lever is carried upward by the projection S on the piston 1. Thus the cut-off end of the piston is 100 held and timed to admit water through the induction-port on one side of the piston, while it exhausts through the exhaust-port through gate D on the other side of said piston at the

rear end of the flume. The plate G of the piston, if left entirely free at the outer end, would be automatically tilted by the action of the water as the central joint of the piston moves up and down, thus serving as a cut-off; but said plate might be liable to tilt before the piston-rod had completed its stroke, and to obviate this difficulty I employ the stops e^5 , before described. These stops are provided with a set-screw Z for throwing the end of the springs n in or out, and thus adjusting them according to the exact lengthening and shortening of the piston.

Referring to Fig. 3, D is a vertically-sliding gate to the induction-ports, said gate having a central opening, through which the water exhausts. This gate slides in roller-bearings v, as here shown; but the rollers may be dispensed with. The gate is moved up and down by the walking-beam H and the rod E, said rod being pivoted at the upper end to the end of said walking-beam and to the gate at the lower end at u. The walking-beam is fulcrumed at w and is actuated by the eccentric y. (Shown in Fig. 6.) When the piston-rod moves down, the gate D moves up and opens the exhaust-port above the end of the piston and closes the port below. This position of the piston and gate D is shown in Figs. 1 and 3, in which the water is supposed to be exhausting through the upper exhaust-port and entering the lower induction-port between the lower gate a and the end of the piston, Fig. 2,

and of course when the piston-rod moves upward the reverse action takes place as to the 35 exhaustion and induction of the water.

Having thus described my invention, what I claim as new, and desire to secure by Letters Patent of the United States, is—

1. The combination of the flume, the piston composed of the two plates end to end and jointedly attached to each other, the piston-rod and power-shaft, the pitman pivotally connecting said shaft and piston-rod, said piston-rod being provided with the projections, the centrally-pivoted lever which is operated by the contact of the end of said lever with the projections, a rod pivoted at the upper end to the other end of said lever and at the lower end to the front end of the piston, 45 and the yielding stops, against which the free end of the piston catches, substantially as set forth.

2. In a motor, the combination of the flume, the jointed piston, as described, a power-shaft, 55 the piston-rod, the walking-beam operated by said shaft, the exhaust-gate, and the rod connected to said gate and to the end of the walking-beam, substantially as set forth.

In testimony of the foregoing I have here- 60 unto subscribed my name in presence of two witnesses.

HENRY E. TRUMBLE.
